UNITED STATES PATENT OFFICE.

WILLIAM NICHOLS BEARDSLEY, OF BRIDGEPORT, CONNECTICUT.

DESIGN FOR A BRACKET FOR BICYCLE-AXLE LAMPS.

SPECIFICATION forming part of Design No. 24,948, dated December 3, 1895.

Application filed October 28, 1895. Serial No. 567,199. Term of patent 3½ years.

To all whom it may concern:

Be it known that I, WILLIAM NICHOLS BEARDSLEY, a citizen of the United States, residing at Bridgeport, in the county of Fairfield and State of Connecticut, have invented and produced a new and original Design for Bicycle-Axle Lamp-Brackets; and I do declare the following to be a full, clear, and exact description of the same, reference being had to the accompanying drawing, forming a part thereof.

The accompanying drawing represents a view in perspective of a lamp-bracket adapted to be applied to the axle of a bicycle.

The leading feature of my design is the upright lantern-support A, having the rearwardly-projecting guide-flanges B B.

C is an elongated opening in the upright A.

D is a horizontal arm supporting the said upright having the double circular end E F. 20

G is a short arm bent at right angles to the arm D, whose extreme end is preferably rounded, as shown.

H is a hole formed through the short arm G to admit the axle of the bicycle. 25

What I claim is—

The design for a bicycle-axle lamp bracket, as herein described and shown in the accompanying drawing.

In testimony whereof I affix my signature 30 in presence of two witnesses.

WILLIAM NICHOLS BEARDSLEY.
